(57) **CLAIM**

The ornamental design for a gaming machine, as shown and described.

DESCRIPTION

FIG. 1 is a front perspective view of a gaming machine showing our new design;

FIG. 2 is a front view thereof;

FIG. 3 is a right side view thereof;

FIG. 4 is a left side view thereof; and,

FIG. 5 is a top view thereof.

The broken lines immediately adjacent to a shaded area define the bounds of the claimed design and form no part thereof. The curved oblique line shading shows that the surface is a transparent, translucent, highly polished or reflective surface. The broken lines depicting the remainder of the gaming machine illustrate environmental structure and form no part of the claimed design.
